(57) **CLAIM**

The ornamental design for a tie-bar for a chromatography column, as shown and described.

DESCRIPTION

FIG. 1 is a perspective view of the tie-bar for a chromatography column showing our new design.

FIG. 2 is a front view of the tie-bar for a chromatography column of FIG. 1

FIG. 3 is a back view of the tie-bar for a chromatography column of FIG. 1.

FIG. 4 is a left side view of the tie-bar for a chromatography column of FIG. 1.

FIG. 5 is a right side view of the tie-bar for a chromatography column of FIG. 1.

FIG. 6 is a top plan view of the tie-bar for a chromatography column of FIG. 1; and,

FIG. 7 is a bottom plan view of the tie-bar for a chromatography column of FIG. 1.
